(57) **CLAIM**

The ornamental design for a package for a personal care product, as shown and described.

DESCRIPTION

FIG. 1 is a top, front, left side perspective view of a package for a personal care product showing our new design;

FIG. 2 is a side elevational view thereof;

FIG. 3 is a top plan view thereof;

FIG. 4 is a bottom plan view thereof

FIG. 5 is a top, front, left side perspective view of a second embodiment of a package for a personal care product;

FIG. 6 is a side elevational view thereof;

FIG. 7 is a top plan view thereof; and,

FIG. 8 is a bottom plan view thereof.

The broken lines in FIGS. 1, 5 & 7 of the drawings are for illustrative purposes only and form no part of the claimed design. The applied angled surface shading shown in FIGS. 5-7 is to show a reflective surface.
